UNITED STATES PATENT OFFICE.

CLARENCE H. LARSEN AND JONATHAN L. SNYDER, OF LINCOLN, NEBRASKA.

STORE-WINDOW STRUCTURE.

Application filed December 15, 1923. Serial No. 680,851.

To all whom it may concern:

Be it known that we, CLARENCE H. LARSEN and JONATHAN L. SNYDER, citizens of the United States, residing at Lincoln, in 5 the county of Lancaster and State of Nebraska, have invented certain new and useful Improvements in Store-Window Structures, of which the following is a specification, reference being had to the accompanying drawings.

This invention relates to window structures and particularly to store fronts.

One of the objects of the invention is to provide a construction of this character in 15 which the window sash or plate glass of the window is firmly, yet yieldably, held in place so as to permit expansion and contraction of the plate glass and of the allied parts.

20 A further object is to provide means for draining off the moisture which condenses on the inner face of the sash or plate glass, said means permitting ventilation which, of course, tends to reduce the condensation of moisture, and a further object in this connection is to provide for controlling the effective size of the drainage openings by the provision of a shiftable damper.

Still another object is to provide means 30 which will permit the ready detachment of the sash when required and the replacement thereof and means for supporting the lower edge of the sash on a cushion of yieldable material.

35 Other objects will appear in the course of the following description.

Our invention is illustrated in the accompanying drawings wherein:—

Figure 1 is a fragmentary elevation of 40 the lower portion or sill of a store window constructed in accordance with our invention;

Figure 2 is a section on the line 2—2 of Figure 1;

45 Figure 3 is a section on the line 3—3 of Figure 1;

Figure 4 is a fragmentary perspective view of the window sill and allied parts.

Referring to these drawings 50 designates the window sill proper and 11 the sash stop mounted upon the window sill in any suitable manner. This sash stop has a width less than the width of the window sill so as to provide a vertically extending shoulder 10 inward of the face of the window sill. The

upper face of the stop is longitudinally cut away adjacent the front of the stop to form a gutter.

Extending over the upper face of the stop 11 and into said gutter downward over the 60 side of the shoulder and over the upper face of the window sill is a sheathing, designated generally at 12, of thin sheet metal. This is formed so as to provide a horizontal portion 13, a downwardly and inwardly extending overhanging portion 14, a downwardly and forwardly extending portion 15 which constitutes the bottom of the gutter, a downwardly extending portion 16 which constitutes the face of the shoulder, and a 70 horizontal portion 17 which extends over the upper face of the window sill beyond the shoulder. Preferably this metal sheathing is extended downward over the front face of the window sill, as at 18, and as illustrated this front face is formed with two longitudinally extending beads 20. This sheet sheathing 12 may be attached to the faces of the window sill and stop in any suitable manner. 80

Resting upon the horizontal portion 17 and disposed against the shoulder 16 are a plurality of longitudinally extending channeled blocks 21. These are spaced from each other to provide openings between the 85 blocks as best shown in Figure 1. Resting upon the series of supporting blocks 21 is a cushion 22 which is preferably made of rubber or other material may be used. The downwardly extending face 16 of the metal 90 sheathing 12 is formed at intervals with the drainage ports or channels 23 which converge downward and terminate at the horizontal face 17 of the sheet. Disposed upon the portion 15 of the sheathing 12 or, 95 in other words, disposed in the gutter or channel formed by cutting away the upper face of the stop 11 is a damper plate 24 which is sufficiently shorter than the total length of the channel 15 to permit the damper plate to be shifted longitudinally. This damper plate at its rear edge has an upwardly and forwardly extending flange fitting against the overhanging shoulder 14 and the damper plate is also formed at intervals with ports 26 adapted to register with the ports 23 when the damper plate is shifted into one position. Obviously, the damper plate may be shifted to carry these openings 26 entirely out of register or par- 110

tially into register and thus the effective area of the drainage ports may be controlled.

For the purpose of holding the sheet of plate glass 29 in place we provide a sheet metal molding 27 whose upper edge is upwardly flanged, as at 28, to bear against the glass 29 while its lower edge rests upon the horizontal portion 17 of the sheathing 12 upon the exterior of the glass. In order to hold the molding 27 in place we provide the wood screws 30 which pass through the molding at intervals and extend through the cushion 22 and are engaged with expansible anchoring members 31 of any ordinary or suitable form which are embedded in the stop 11. The lower edge of the molding 27 is provided at intervals with outlet ports 32 which are in alignment with the channels 15 or ports 23 and with the spaces between the supporting blocks 21. Thus it is obvious that any water which may collect upon the plate glass 29 and run down into the channel 15 will, if the damper plate 24 is shifted to open the ports 23, run down onto the portions 17 and pass out between the blocks 21 and out through the drainage openings 32 and obviously these openings 32, the spaces between the blocks 21 and the channels 23 will permit ventilation of the interior of the window thus tending to reduce condensation.

While we have heretofore described a structure in which metal sheathing is carried down over the face of the sill 10, we do not wish to be limited to this as the apron 18 which extends down over the face of the sill may be omitted and the portion 17 may terminate at the upper face of the sill. This is particularly desirable where the window sill is of stone or where the construction illustrated in Figures 2 and 3 is used at the jambs of the window. While we have illustrated a construction which is particularly adapted for the sills of store or display windows, it is obvious that the same construction might be used for the jambs of the window, this construction permitting ventilation.

The sheet of plate glass 29, which is subjected to considerable strain by reason of expansion and contraction, is yieldably supported not only by the cushion 22 but by the sheet metal molding 27 and the upper flange 28 of this molding engages the margin of the window beyond the point of engagement of the shoulder 16 with the plate glass. Thus while the plate glass is firmly clamped in place a certain amount of yielding movement is permitted which will tend to prevent the glass from being broken under wind pressure or other stresses and which will permit not only expansion and contraction of the glass itself but of the metal framing parts. While we do not wish

to be limited to any particular material, we have found that sheet copper is preferable for the sheathing 12 and for the molding 27. Obviously, the structure might be changed in many ways without departing from the spirit of the invention as defined in the appended claims. 70

We claim:—

1. In a window structure, a longitudinally extending member and a stop mounted thereon, the outer face of the stop constituting a shoulder, a supporting block disposed on the member and against the stop, a cushion on the supporting block, a sheet of glass having its edge disposed against the cushion and its margin disposed against the stop and an exterior sheet metal molding resting at one edge against the longitudinally extending member and at its other edge bearing against the sheet of glass on a line 80 nearer the center of the sheet of glass than the line of engagement between the stop and sheet of glass, and fastening devices engaged at their outer ends with the molding and extending through the molding from 90 the exterior thereof and extending into and engaged with the stop, the sheet of glass being yieldingly engaged and held in place entirely by the sheet metal molding whereby the sheet metal molding may flex to permit expansion and contraction. 95

2. In a window structure, a longitudinally extending member, a stop carried thereby, the outer face of the stop constituting a shoulder, a supporting means disposed on the member and against the stop, a sheet of glass having its edge operably supported by the supporting means and having its margin disposed against said shoulder, an outer sheet metal molding resting at one edge 100 against the longitudinally extending member and at its inner edge bearing against the glass, and fastening devices engaging the sheet metal molding and extending into the stop and operably engaged therewith, 105 that face of the stop on the inside of the glass and extending inward therefrom having a longitudinally extending channel, the shoulder formed on the stop being provided with channels extending to the longitudinally extending member, the molding having apertures on its lower edge and the supporting means being formed to provide openings communicating between said channels and said apertures. 110

3. In a window structure, a longitudinally extending member, a stop carried thereby, the outer face of the stop extending at right angles to the longitudinally extending member, a lining sheathing extending over certain of the faces of the stop and over the face of the longitudinally extending member, a series of supporting blocks resting against the longitudinally extending member and against said shoulder, a cushion 125

- mounted thereon, a sheet of glass having its edge bearing against said cushion and its margin bearing against the shoulder, an outer sheet metal molding bearing at one 5 edge against the member and at its other edge bearing against the glass outward of the corners of the shoulder and fastening devices passing through the molding and the cushion and extending into the stop, that 10 face of the stop adjacent the glass being formed to provide a longitudinally extending channel and the sheet metal sheathing lining said channel, said sheathing being formed at intervals with ports leading from 15 said channel to the point of juncture between the stop and the longitudinally extending member, the molding being formed with ports and the supporting block being formed to provide passages leading from 20 said first named ports to the outlet ports, and a controlling damper mounted in said channel and controlling the effective area of 25 said ports.
4. In a window structure, a member against which the plate glass of the window abuts, said member being formed with a longitudinally extending channel having outlet ports leading past the edge of the glass, and a damper plate longitudinally 30 shiftable in said channel to control passage through said ports.
5. In a window structure, a sill, a longitudinally extending stop mounted thereon,
- the front face of said stop constituting a shoulder, means for supporting a sheet of 35 plate glass against the front face of the stop and against said shoulder, the stop adjacent the glass being formed with a longitudinally extending channel, the inner wall of the channel being overhanging, the shoulder 40 being formed with vertical ports communicating with the channel, and means being provided to permit the discharge of liquid from said ports to the exterior of the sill, and a longitudinally shiftable damper plate 45 mounted in the channel and having ports adapted to register with the ports in the face of the stop, the rear edge of said damper plate having an overhanging flange fitting beneath the overhanging wall of the 50 channel.
6. In a window structure, a longitudinally extending member, a stop mounted thereon, the front face of the stop constituting a shoulder, a sheet of glass having its margin 55 disposed against the stop, and an outer sheet metal molding operatively supported upon the longitudinally extending member and having its inner edge yieldingly bearing against the plate of glass on a line nearer the 60 center of the plate of glass than is the outer edge of the molding.

In testimony whereof we hereunto affix our signatures.

CLARENCE H. LARSEN.
JONATHAN L. SNYDER.
